LEAD DISPENSERS

William E. Danjczek, Easton, Pa., assignor to L. & C. Hardtmuth, Inc., Bloomsbury, N. J., a corporation of New Jersey

Application June 25, 1956, Serial No. 593,705

8 Claims. (Cl. 221—199)

This invention relates to dispensing devices in general and particularly to a holder for graphite drafting leads provided with means for moving such leads, one by one, into position at which they can be inserted directly into a holder without the requirement of handling them.

One of the objects of this invention is the provision of a simple, inexpensive combination lead holder and lead dispenser adapted to receive a plurality of drafting leads, and which dispenser is equipped with an ejector for propelling one of the leads at a time for a distance so that a portion of the lead will extend from the dispenser, and wherein a yieldable lead stop or a gate is provided at one end of the dispenser for normally holding the leads therewithin, and which gate is adapted for movement to its opening position by a lead being either ejected from the dispenser or injected therewith.

Another object of this invention is the provision of a lead dispenser composed of a box-like, lead-holding case having side walls and end walls, and within which walls fits a detachable and reversible closure or cover, and wherein from one face of the cover extend spacing means which serve for increasing the distance between the cover and the bottom of the case.

The foregoing and numerous other objects and important advantages of the present invention will become more fully apparent from the ensuing description in conjunction with the accompanying drawings, wherein:

Fig. 1 is a perspective view of the device in accordance with the present invention;

Fig. 2 is a longitudinal section therethrough along approximately lines 2—2 of Fig. 1;

Fig. 3 is an enlarged transverse section taken along lines 3—3 of Fig. 1;

Fig. 4 is a similar enlarged transverse section taken along lines 4—4 of Fig. 1;

Fig. 5 is a transverse cross section taken approximately along lines 5—5 of Fig. 1;

Fig. 6 is a plan view of the cover for the device;

Fig. 7 is a side elevation of the cover;

Fig. 8 is a plan view of the device with the cover removed and holding a plurality of substantially thin leads, and illustrating the manner in which one of the leads is being ejected;

Fig. 9 is a plan view of the device similar to that shown in Fig. 8 but provided with a cover and containing a lesser number of larger leads;

Fig. 10 is a longitudinal cross section through the device approximately along lines 10—10 of Fig. 9;

Fig. 11 is a side elevation of the case as seen when looking at the top of Fig. 8;

Fig. 12 is a side elevation of the case seen from the bottom of Fig. 8;

Fig. 13 is a section taken approximately along lines 13—13 of Fig. 9; and

Fig. 14 is a perspective view of the lead ejector.

In the drawings numeral 10 indicates an elongated, box-like, open-top, lead-receiving case, having side walls 11 and 12 and end walls 13 and 14. Adjacent to wall 13 is a cover rest 15 and adjacent to wall 14 is another cover rest 16. Both of these rests are lower than end walls 13 and 14.

2

Both side walls 11 and 12 are provided with longitudinal recesses 17 and 18, respectively, as clearly seen in Figs. 12 and 11. Recess 18 of side wall 12 is of lesser depth than recess 17 of side wall 11. At approximately the middle of side wall 11 there is a raised step formation 19, the upper face of which is disposed in the same plane as the upper face of recess 18 in side wall 12. In addition recess 17 has a sub-recess 20 at a lower level than the upper face of recess 17, the purpose of which sub-recess shall be explained presently.

Both end walls 13 and 14 have shallow, short recesses 13' and 14' at their top edges. These recesses serve as guides for the attachment of closing tapes, as will be presently evident. In cover rest 15 next to end wall 13 is a cavity in which is operatively mounted a lead stop or gate element 21 in the shape of a disc having a stem 21' engaged by a spring 22, the latter normally urging element 21 toward the inner face of side wall 11, as clearly seen in Figs. 8 and 9. At that position element 21 prevents lead contained in the case from voluntarily or accidentally leaving the latter. However, when a lead is being either ejected from or injected into the case, lead stop 21 will yield to permit the lead to pass.

As will be seen in Figs. 1, 8 and 9, end wall 13 does not extend fully to side wall 11, whereby a sufficiently large space or recess 23 is provided between these two walls to permit passage therethrough of lead being either ejected from or inserted into the case. At end wall 14 cover rest 16 forms an enclosure which is distanced from wall 11 so that a recess 24 is formed. Cover rest 16 is provided with vertical lugs 16' for supporting the extreme edge of the cover.

Recess 24 between cover rest 16 and side wall 11 is adapted to accommodate a movable ejector 25 which is operable from without the case and slides along the recessed portion of wall 11. Sub recess 20 in recess 17 facilitates the attachment of the ejector to wall 11. As seen in Figs. 1, 8, 9 and 14 this ejector is provided with a depression or notch 25' adapted for engaging the pointed end of a lead as the ejector is moved toward lead stop 21.

The cover 26 for the case is best illustrated in Figs. 6 and 7, and is composed of narrow and wider portions 27 and 28, respectively. Narrow portion 27 is adapted to fit between walls 11 and 12 at the left half of the case, as shown in Figs. 1, 3 and 9, whereas wider portion 28 is adapted to extend with its edges over the side walls, that is over the recesses 17 and 18. The end of wider portion 28 is recessed as at 29 to fit between wall elements 30 at the right hand end of the case and forming the right hand termini of recesses 17 and 18.

From one face of the cover there extend two pairs of parallel spacing elements 31 and 32 at the cover ends and central spacing elements 33, all of the spacing elements being of a uniform height. When cover 26 is placed with these spacing elements directed downwardly so that they rest against cover supports 15 and 16, as seen in Figs. 10 and 13, the distance between the underface of the cover and the case bottom is greater than it would be when the spacing elements point upwardly as illustrated in Figs. 2, 3 and 4. It is to be noted that the central spacing means 33 will support the cover at the center as they abut with the upper face of recess 18 and with the upper face of raised step formation 19 at the center of the case adjacent to the left hand end of recess 17. The position of the cover with the spacing elements directed downwardly is intended to provide sufficient space for leads of large diameters as seen in Figs. 9, 10 and 13. Since only six leads of the large diameter can be placed into the case, the remaining space between wall 12 and the uppermost lead is filled with a suitable spacer 34 which is removable. Obviously, the case can hold twelve leads of a small diameter, as clearly seen in Fig. 4,

in which event cover 26 rests with its smooth face against end supports 15 and 16 while spacing elements 31, 32 and 33 point upwardly.

When the case is to be closed, the narrow portion of cover 26 is positioned within the left wall ends and the recessed end of the wider cover portion is placed between wall elements 30. Now the cover is secured to the case by means of pressure-sensitive tapes indicated at 35 in Fig. 1. This is done by first attaching one end of the tapes to the cover end so that they pass over recesses 13' and 14' provided at the upper edge of end walls 13 and 14, respectively, whereupon the tapes are swung against the bottom of the case and there are attached. It is preferred that the tape ends which are placed on top of the cover bear indices to denote the degree of leads placed into the case. It is also preferred to secure the upper end of spring 22 of lead stop element 21 to the upper end of the recess provided for the spring in cover rest 15.

Operation

The filling of the case is a simple procedure. The leads are placed with their pointed ends in the direction towards cover rest 16, while the blunt ends of the leads face cover rest 15. When the case is filled the cover is placed over it. When twelve thin leads 35' are employed, as shown in Figs. 4 and 8, the smooth cover face reposes over rests 15 and 16 and spacers 31, 32 and 33 extend upwardly from the cover. When, on the other hand, large diameter leads 36 are used, as shown in Figs. 9 and 13, first compensating spacer 34 is placed against side wall 12, whereupon the leads are again positioned with their pointed ends towards cover rest 16. Now the cover is placed with its spacing means 31, 32 and 33 in downward position. Obviously in either event it is essential that before filling the case with leads, ejector 25 is secured to the recessed portion of side wall 11. This is done by simply placing the ejector against sub-recess 20; thereupon positioning ledge 25" (see Fig. 14) against the case bottom and then pushing head 125 over the upper face of sub-recess 20 (see Fig. 12). Now the ejector is moved into the position shown in Fig. 9, that is, with head 125 within recess 24, whereupon the filling of the case with leads is effected. Now the cover is attached to the case by means of tapes 35.

To eject one lead at a time, ejector 25 is moved in the direction towards end wall 13. The pointed end of the lead to be ejected is engaged by recess 25' provided in head 125 of the ejector. As the lead progresses it lifts lead stop 21 and the lead passes out of the case through recess 23 between end wall 13 and side wall 11. When a sufficient portion of the lead extends from the case it can be directly gripped by the collet of the lead holder 37, as shown in Fig. 8. Thus the user of the device need not touch a lead ejected from the case.

While in the foregoing a specific construction of the device is described in connection with the drawings, it is quite obvious that in actual production changes and improvements may be required, such changes and improvements being deemed to reside within the scope of the present invention, as defined in the annexed claims.

What is claimed as new is:

1. In a lead holder and lead dispenser, the combination with an elongated, box-like, open-top, lead-receiving case having partly recessed side and end walls and cover rests adjacent to and lower than both of said end walls, of a removable and reversible cover having a narrower and a wider portion placed over and adapted to close the open top of the case and fitting within corresponding portions of the case walls and supported by said cover rests, the cover rest adjacent to one of the end walls as well as that one end wall being spaced from one of the side walls to provide a passage for a lead, a lead ejector operatively associated with and movable along the recessed portion of that one side wall, and a substantially disc-shaped mobile lead stop operative within the cover

rest adjacent to that one end wall and forming a normally closed gate for said passage and being operable to its opening position by leads either ejected from or injected into the case, the cover rest adjacent to that other end wall being spaced from that one side wall to provide a recess for receiving said lead ejector in its inoperative position.

2. In a lead holder according to claim 1, and wherein the recesses of the partly recessed side walls being longitudinal and of substantially an equal length and serving for the reception of the wider cover portion, the recess in that one side wall being deeper than the recess in the other side wall, said ejector being operative along said deeper recess and beneath the wide cover portion, said deeper recess terminating in a raised step formation located substantially midway of that one side wall and serving as stop for said ejector, the upper face of that step formation and the upper face of the recess in that other side wall being disposed in substantially the same plane, and a short sub-recess in that deeper recess of that one side wall for facilitating the mounting and attachment thereto of the lead ejector.

3. In a lead holder according to claim 2, and wherein said lead stop constitutes a spring-loaded element normally bearing against the inner face of that one side wall.

4. In a lead holder according to claim 3, and wherein one end of the lead ejector has a notch for engaging the end of a lead preparatory to ejecting the lead from the case.

5. In a lead holder according to claim 2, and wherein the longitudinal recesses in the side walls extend from substantially their center to aligned points slightly distanced from said other end wall.

6. In a lead holder according to claim 5, and wherein the narrow and wider cover portions extend from substantially the center of the side walls to and abutting with the end walls, the wider cover portion extending over the longitudinal recesses in the side walls and having a reduced end corresponding in width to that of the narrow cover portion.

7. In a lead holder according to claim 2, and wherein spacing means project from one face of the cover at both its ends and substantially at its center to facilitate increasing the distance between the cover and the case bottom by placing the spacing means at the ends of the cover against the cover rests adjacent to the end walls, and the center spacing means against the upper face of that step formation at that one side wall and against the upper edge of the longitudinal recess in said other side wall.

8. In a lead holder according to claim 7, and wherein the recesses in the end walls are located centrally, and wherein the spacing means at the ends of the cover constitute pairs of parallel bars, the distance between the bars substantially corresponding to the length of said recesses in the end walls, these recesses and areas between the spacing bars serving as guides for fastening means adapted to secure the cover in closing position against the case when the cover is placed over the case with its spacing means projecting upwardly.
